DESIGN FOR A LAMP BRACKET

Jacob A. Mehr, St. Louis, Mo.

Application April 30, 1949, Serial No. 2,360

Term of patent 7 years

(Cl. D48—4)

To all whom it may concern:

Be it known that I, Jacob A. Mehr, a citizen of the United States, residing in the city of St. Louis, State of Missouri, have invented a new, original, and ornamental Design for a Lamp Bracket, of which the following is a specification, reference being had to the accompanying drawing, forming a part thereof.

In the drawing:

Fig. 1 is a perspective view of a lamp bracket, showing my new design;

Fig. 2 is a top plan view thereof, and

Fig. 3 is a front elevational view thereof.

I claim:

The ornamental design for a lamp bracket, substantially as shown.

JACOB A. MEHR.
